Primary Examiner — Cynthia Underwood(74) Attorney, Agent, or Firm — Robert C Montgomery; Montgomery Patent & Design, LP(57) CLAIM

The ornamental design for a cable organizing device, as shown and described.

DESCRIPTION

FIG. 1 is a perspective top side lid open view of the cable organizing device, showing my new design;

FIG. 2 is a perspective top side lid closed view of the cable organizing device;

FIG. 3 is a left side view thereof;

FIG. 4 is a front side view thereof;

FIG. 5 is a back side view thereof; and,

FIG. 6 is a top side view thereof.
